UNITED STATES PATENT OFFICE.

LUDWIG NEUMAYER, OF STRASSBURG, GERMANY.

VENDING-MACHINE.

1,039,580.

Specification of Letters Patent. Patented Sept. 24, 1912.

Application filed December 19, 1911. Serial No. 666,781.

To all whom it may concern:

Be it known that I, LUDWIG NEUMAYER, a subject of the Emperor of Germany, and resident of Strassburg, Germany, have invented certain new and useful Improvements in Vending-Machines.

This invention relates to improvements in vending machines.

The object of the invention is to provide a vending machine operated by two or more independent coins, one of which acts to operate devices for venting the article or liquid to be dispensed.

The invention also relates to improvements in the details of construction and arrangement of parts which will be herein-after described and particularly pointed out in the claims.

In the drawings: Figure 1 is a side elevation, partially in section of my improved machine. Fig. 2 is an end elevation, partially in section.

The numeral 54^a indicates a casing provided in the lower portion with glass panels 27 and 43 to expose the coins to view, during the operation of the mechanism. A shaft 10, extends through the casing and has secured thereto a disk 9 having formed in its periphery a plurality of concave notches 9^a to receive a coin. The shaft 10 is continuously revolved by any suitable mechanism not shown for a purpose to be described. Located adjacent the disk 9 is a coin chute 18 which extends upwardly and forwardly toward the front wall of the casing as shown in Fig. 1. The chute 18 is formed with a branch 18^a to direct a coin to one of the concave notches 9^a in the disk 9. Co-operating with the upper portion of the coin chute 18 and adapted to form a continuation thereof, is a gate 1 pivoted at 1^a and provided with a crank arm 38. To the outer end of the crank arm 38 is pivoted a lever 7, the lower end of which is pivoted to an arm 36^a of a bell crank lever 35, mounted on a pivot 36. To the other arm 37 of the bell crank lever is pivoted a link 32, connected by a link 31 with a counter 30.

Pivoted at 49 above the disk 9 is a bell crank lever 8^a one arm 8 of which is pivoted at 48 to the lever 7. The other arm 55 of said bell crank lever is in the form of a segment and is provided with a slot 50 and at its lower forward end is mounted a roller 47, against which the periphery of the disk

9 bears. In advance of the disk 9, is a latch lever 47 pivoted at 46 and formed with a cam surface 47^a near its upper end and nearer its lower portion it is provided with a roller 45 which is located adjacent the periphery of the disk 9. To the lower extended end of the lever 47 is attached a spring 26, the opposite end of which is attached to the lower end of a coin holding lever 12. The coin holding lever 12 is pivoted at 14 and projecting from its upper end is a stud 13, which extends through the slot 50 in the crank lever 8^a. At a suitable point some distance above the pivot 14, a pin 16 extends from the coin holding lever 12 and into the chute 18 below the bottom of the branch 18^a also extending from the lever 12 at a suitable point below the pivot 14 is a pin 29 which extends into the chute 18. The pins 16 and 29 form supports for the coins during the operation of the machine as will be described later on.

The lever 7 is formed with a slot 24 in which fits a pin 25 on the end of a lever 19 pivoted at 23. The rear end of lever 23 is formed with a lateral portion having a threaded opening to receive a screw 20. Located in the path of movement of the end of the screw 20 is a normally outwardly spring pressed valve stem 28^a of a valve 28 which controls the liquid dispensed through a pipe 41.

Adjacent the gate 1 is a hopper 2 which communicates with a chute 3 leading to a cup 4. This arrangement is for the purpose of returning a coin to a customer if perchance there be inserted a second coin in the machine before the mechanism had completed the operation started by the introduction of the previous coins.

In operation the gate 1 is normally in the position shown in full lines in Fig. 2, that is to say the lever 7 is in its lowest position, as shown in Fig. 1, and the gate is in registry with the chute 18. The shaft 10 is continually rotated so that when the coins are introduced, one will be caught in one of the notches 9^a to effect the operation of the mechanism. A coin is inserted in the opening communicating with the chute, and is held suspended by the pin 16 at the point indicated at d in Fig. 1, then a second coin is introduced and when it strikes the first coin d it will roll in the branch 18^a of the chute and into one of the notches 9^a as indi-

cated at *c*. As the disk 9 revolves in the direction of the arrow *b*, coin *c* will contact with the roller 11 and rock the crank lever 8^x in the direction of the arrow *a*, and through the pivotal connection 48, the lever 7 will be raised. When lever 7 is moved up, it rocks the gate 1 to the dotted line position shown in Fig. 2 so as to permit a coin if inserted after the parts have thus moved 10 to fall into the hopper 2, and thence to the cup 4 where the customer can get it. The turning of the crank lever 8^x causes the wall of the slot 50 to engage the stud 13 and rock the coin holding lever 12 to remove 15 the pin 16 and permit the coin at *d* to fall. The rocking of said lever however positions pin 29 in the path of the coin consequently the latter is again supported in the chute. When lever 7 is raised the pivot pin 48 will 20 ride over the cam portion of the latch lever 47 and spring 26 will pull the upper end of said lever under said pin and hold the parts in this position and will move the roller 45 in the path of movement of the coin *c*. The 25 raising of lever 7 also rocks the lever 19 and causes the end of the screw 20 to force the spring pressed valve stem down and open the valve and permit the liquid to pass through the pipe 41. Upward movement 30 of lever 7 performs another function in that through the connections 35—33 and 31 the inclined plate 34 is rocked in the direction of the arrow 51 to deposit the previously introduced coins to the draw 54 and 35 also to operate the counter 30. Now as the disk 9 continues to revolve the coin *c* will contact with the roller 45 and rock lever 47 and thereby remove the upper end from under the pivot 48 and permit crank lever 40 8^x to assume its normal position, and through the spring 26 and the wall of the slot 50 the coin holding lever will be rocked on its pivot and returned to normal position, withdrawing the pin 29 from under the coin 45 to permit the latter to drop and slide down on the plate 34 where it will be exposed to view through the glass panels. The parts are so timed that coin *c* will fall from its notch about the same time coin *d* falls from 50 the pin 29. During the time the coin *c* is traveling from the roller 11 to roller 45 the liquid is flowing through the pipe 41, then when the lever 47 is released and is assuming its normal position the spring valve will 55 gradually close the slot 24, permitting of this movement after lever 7 is lowered.

Obviously if it be desired to arrange the parts so that it will require the introduction of three coins instead of two to operate the 60 mechanism the only changes necessary to make is to locate the pin 16 at the point indicated at 15 in Fig. 1. Under these circumstances the first coin indicated at *d'* will be supported on a pin inserted at 15 65 and the second coin indicated at *d* will be

supported on coin *d'*. The third coin would then be directed to the branch 18^a as before described.

Claims:

1. In a vending machine, the combination of a rotating shaft, a disk mounted on the shaft and formed on its periphery with a series of coin seats, a chute formed with a branch chute to direct a coin to the coin seats, a coin holding lever having a pin 75 which extends into the coin chute to temporarily support a coin so that upon the introduction of a subsequent coin it will strike the one previously introduced and will be directed to the branch chute, a crank lever 80 having a roller located adjacent the periphery of the disk and operatively connected to the coin holding lever, a setting lever pivoted to the crank lever, a lug extending from the setting lever, a pivoted arm having a roller normally held away from the periphery of the disk, a spring for rocking the arm into the path of the lug when the setting lever is elevated, a dispensing device 85 and a connection from the setting lever and the dispensing device for operating the latter when a coin is caught in one of the seats and rocks the crank lever, the said coin in the seat subsequently operating the arm and releasing the setting lever. 90

2. In a vending machine, the combination of a rotating disk formed on its periphery with coin seats, a chute formed with a branch to direct a coin to the coin seats, a pivoted coin holding lever having pins 100 which extend into the chute below the branch thereof, a pivoted crank lever operatively connected to the coin holding lever, a roller extending from the crank lever adjacent the periphery of the disk, a 105 setting lever pivoted to an arm of the crank lever, a lug extending from the setting lever, a pivoted arm having a roller normally held away from the periphery of the disk, the upper end of said arm being held by 110 the lug when the setting lever is raised, a spring connecting the arm and the coin holding lever, said spring serving to normally hold the coin holding lever in position to locate the upper pin in the path of a 115 coin introduced in the chute and support the same, dispensing means, a lever between the setting lever and the dispensing means to operate the latter when the former is raised, the coin previously introduced in the chute 120 acting as a guide to direct a subsequent coin to one of the coin seats, the said coin acting on the crank lever to operate the dispensing means and release the coin on the pin and subsequently acting on the roller on the arm 125 to reset the parts.

3. In a vending machine the combination of a rotating disk formed with coin seats, a chute having a branch to direct a coin to one of the seats in the disk, means for tem- 130

porarily supporting a coin in the chute on which a subsequently introduced coin falls and is directed to the branch in said chute, dispensing mechanism, means operated by 5 the coin in the seat for operating the dispensing mechanism, and means with which said coin operates to subsequently release the temporarily supported coin.

4. In a vending machine, the combination 10 of a rotating disk formed with coin seats in its periphery, a chute formed with a branch, means including a pivoted lever and pins extending therefrom to temporarily support a coin adjacent the branch in the 15 chute and subsequently catch and hold the coin for a definite period after having been released from its temporary position, a dispensing device, means including pivoted levers operable by a coin held in one of the 20 seats for operating the dispensing device and releasing the temporarily supported coin, and means subsequently operated upon by said coin for finally releasing the coin.

5. In a vending machine, the combination 25 of a rotating disk formed on its periphery with a series of coin seats, a chute formed with a branch to direct a coin to one of the coin seats, means for temporarily supporting a coin in the chute adjacent the branch 30 therein, a dispensing device, a pivoted lever coöperating with the same to release the said device, and means including a pivoted lever with which a coin held in one of the seats operates to rock the pivoted lever to 35 operate the dispensing device, the said coin in the coin seat coöperating to release the parts and to permit the latter to assume their normal position.

6. In a vending machine the combination 40 of a rotating disk formed with coin seats, a chute formed with a branch to direct a coin to one of the coin seats, means for temporarily holding a coin in the chute adjacent the branch thereof whereby when a 45 subsequent coin is introduced it will pass to one of the coin seats, a dispensing device, means operated by the coin in the seat for releasing the temporarily supported coin and operating the dispensing device, means 50 for again catching and temporarily supporting the released coin, a rocking plate, a connection between the rocking plate and the means operated by the coin for operating said plate, and means operated by the coin 55 in the seat for setting the plate in closed position and releasing the coin temporarily supported in the chute to permit said coin to fall on the plate.

7. In a vending machine the combination 60 of a rotating disk formed with coin seats, a chute having a branch which directs a coin

to one of said seats, a pivoted lever having two pins adapted to be moved into the path of a coin passing through the chute, a dispensing device, a rocking coin receiving plate, means operable by a coin in one of the coin seats for rocking the pivoted lever to release a coin and to place one of the pins to subsequently hold the coin in said chute to rock the coin plate and to operate the dispensing device, automatic means for holding the parts in this position, and means operable by the coin in the coin seat for releasing the supported coin and returning the coin plate to normal position and means for automatically closing the dispensing device 65 after coin has operated the resetting means.

8. In a vending machine, the combination of a coin chute, a continually rotating disk formed with coin seats, a dispensing device, 80 means for holding a coin introduced in the chute to subsequently act as a guide to direct a subsequently inserted coin to one of the seats in the disk, means operated by a coin in one of the coin seats for operating 85 the coin holding means to release said coin and operate the dispensing device, means for holding the parts in this position during a partial rotation of the disk, said latter means being in the path of the coin in the 90 seat and adapted to be struck thereby to reset the parts to normal position.

9. In a vending machine, the combination of a rotating disk formed with coin seats, a coin chute having a branch to direct coins 95 to the coin seats, means in the chute to temporarily support a coin whereby to direct a subsequent coin to the branch and into one of the coin seats, and means operated by the coin in the seat to release the tempo- 100 rarily supported coin.

10. In a vending machine, the combination of a rotating disk formed with coin seats, a coin chute having a branch to direct a coin to one of the coin seats, means in the chute for temporarily supporting a coin whereby to direct a subsequent coin to the branch and into one of the coin seats, said means also having a second coin support to subsequently hold the coin in the chute, a latch 105 for holding the coin supporting means in position to place the second coin support in the path of the coin in the chute, said latch being operated by the coin in the seat to finally release the coin supported in the 110 chute.

In testimony whereof I have hereunto set my hand in presence of two witnesses.

LUDWIG NEUMAYER.
